US0D1073676S

(12) **United States Design Patent** (10) **Patent No.:** **US D1,073,676 S**
(45) **Date of Patent:** **** May 6, 2025**

(54) **KEYBOARD**

(71) Applicant: **Logitech Europe S.A.**, Lausanne (CH)

(72) Inventors: **Tanyel Yalazoglu**, Geneva (CH);
Sylvain Sauvage, La Tour-de-Peliz (CH);
Martin Caspar Rüegg, Muttenz (CH);
Jasper Phua, Morges (CH)

(73) Assignee: **Logitech Europe S.A.**, Lausanne (CH)

(**) Term: **15 Years**

(21) Appl. No.: **29/945,927**

(22) Filed: **Jun. 5, 2024**

Related U.S. Application Data

(63) Continuation of application No. 29/884,718, filed on Feb. 15, 2023, now Pat. No. Des. 1,035,665, which is a continuation of application No. 29/778,282, filed on Apr. 12, 2021, now Pat. No. Des. 981,411, which is a continuation of application No. 29/699,435, filed on Jul. 25, 2019, now Pat. No. Des. 959,430.

(57) **CLAIM**

The ornamental design for a keyboard as shown and described.

DESCRIPTION

FIG. 1 is a front, top, right perspective view of a keyboard showing our new design;

FIG. 2 is a rear, top left side perspective view thereof;

FIG. 3 is a rear, bottom left side perspective view thereof;

FIG. 4 is a top plan view thereof;

FIG. 5 is a bottom plan view thereof;

FIG. 6 is a front elevational view thereof;

FIG. 7 is a rear elevational view thereof;

FIG. 8 is a right side elevational view thereof; and,

FIG. 9 is a left side elevational view thereof.

The broken lines depict portions of the keyboard that form no part of the claimed design.

1 Claim, 7 Drawing Sheets
